JOHN F. ZACHARIAS, OF LEESBURG, VIRGINIA.

Letters Patent No. 77,430, dated April 28, 1868; antedated April 11, 1868.

IMPROVEMENT IN MACHINES FOR ATTACHING LABELS TO NEWSPAPERS, &c.

The Schedule referred to in these Letters Patent and making part of the same.

TO ALL WHOM IT MAY CONCERN:

Be it known that I, JOHN F. ZACHARIAS, of Leesburg, in the county of Loudon, and the State of Virginia, have invented a new and useful Improvement in Machinery for Attaching Labels upon Newspapers, Journals, &c., by steam or other power; and I do hereby declare that the following is a full, clear, and exact description of the construction and operation of the same, reference being had to the annexed drawings, making part of this specification, in which—

Figure 1 is a side elevation.

Figure 2 is a face view of slotted rod P, detached.

Figure 3 is a longitudinal vertical section.

A represents an oblong square frame; B B', two rollers, one at each end of frame A; C, a slatted carrier, the slats c c, &c., being made of wood or other material, and fastened upon the bands or straps C' C', said slatted carrier C having openings or vacancies D D, &c., in it, wide enough to receive the paper, journal, &c., said slats running across the inside of frame A, the distance from one vacancy or opening, D, to the next opening, D, being exactly equal to the circumference of the roller B. F is a box or feeder, with the folded papers or journals f f f f in it, having the outside measure equal to the width of frame A, the inside being equal to the openings or vacancies D in the slatted carrier C.

On the side of frame A is placed my machine, patented August 13, 1867, No. 67,833, with such changes in that patent as are necessary to adapt it to the present machine, and which changes are shown in these drawings by the letters H I J; said machine being represented in the drawings by the uprights G G. Running transversely across the top of these uprights G G is a shaft, H, resting in proper sockets or boxes. On one end of shaft H is a band-wheel, represented in the drawings by the crank I. Half way between the uprights G G is the eccentric, J. Upon this works the shaft K of sliding gate L, and scissors M. At the other end of shaft H is the crank, N, which is connected to crank, O, by the connecting-rod P, said connecting-rod P having, running through its long diameter, for a distance of twice the length of cranks N or O, a slot, P', which allows it to play upwards or downwards upon the pin P'', thus giving to crank, O, a rotary motion in a reverse direction to crank, N; said pin P'' being placed directly in a line from centre of shaft H and shaft O', and equidistant between the two shafts H and O'. Shaft O' is supported by two brackets, R R', running out from side of frame A. The pin P'' stands at right angles with the connecting-rod P, and is fastened upon the side of the frame of machine G G. On the left-hand end of shaft O' is cog-wheel Q. At right angles with cog-wheel Q is cog-wheel Q', turning upon a short shaft, S, standing out from frame A. Cog-wheels Q and Q' play or work into one another. S' is the point where connecting-rod T works upon cog-wheel Q'; and from thence conveys motion to crank, U, upon roller B. V is an inverted U-shaped opening in end of rod T, intended to allow roller B to remain quiet for an instant, whilst the papers drop into openings D, and receive their directions under sliding gate L. W is an original device, whereby I gain a rotary motion in a reverse direction to cog-wheel Q', said device being placed equidistant from centre of shaft S and centre of the shaft of roller B. X X are two caps over shaft of roller B. X' X' are two caps over shafts of roller B', inclined so that the papers, journals, &c., may fall off from frame A. Y Y are ears or projections running inwards from frame A, for the slatted carrier C to play or slide upon. The devices P'' and W, and the rods P and T, are only different forms of the same mechanical agents, to illustrate the same principle and gain the same motion.

The operation of my machine is as follows: Folded papers, journals, &c., f f f f, being placed in feed-box F, motion is given to band-wheel I, from thence on to eccentric, J, crank, N, crank, O, through connecting-rod P; and by means of pin P'' a rotary motion is given to crank, O, and thus from cog-wheel Q to cog-wheel Q'; thence to crank, U, upon roller B by connecting-rod T, and in a rotary direction upon crank U, by the device W, and thus through the shaft of roller B to roller B; by this to the slatted carrier C, and by the slatted carrier C to roller B'. As the openings or vacancies D D D, &c., pass by feed-box F, a paper, f, drops in, and by a revolution of roller B the paper f is carried under the sliding gate L, receives its direction there, and is thrown off the frame A by means of the caps X' X'.

What I claim, is—

1. The combination of the sliding gate L, and the scissors M M, of an automatic labelling-machine, with the eccentric J, the transmitting-devices P and T, giving proper periods of rest to the carrying-bands C' C', all arranged and combined substantially as set forth.
2. The slotted connecting-rod P, having a compound reciprocating and oscillating motion upon the fulcrum-pin P" for the purpose of transmitting a rotary motion from one crank to another, in combination with the other devices of the machine, substantially as set forth.
3. The combination with the said devices, or their equivalents, for transmitting rotary motion, of the auxiliary slot V in the connecting-rod T, for permitting a rest for the carrying-bands C' C', at every revolution of the roller B, as and for the purpose set forth.

J. F. ZACHARIAS.
